United States Patent Office

Des. 177,802

Patented May 29, 1956

177,802

HOBBYIST'S LATHE OR SIMILAR ARTICLE

Milton Garvin, Cincinnati, Ohio, assignor to
Edward F. Winkle, Cincinnati, Ohio

Application July 29, 1954, Serial No. 31,648

Term of patent 14 years

(Cl. D34—15)

Fig. 1.

Fig. 2.

Fig. 3.

Fig. 1 is a front perspective view of a hobbyist's lathe or similar article, showing my new design;

Fig. 2 is a rear perspective view thereof; and
Fig. 3 is a bottom plan view thereof.

I claim:

The ornamental design for a hobbyist's lathe or similar article, substantially as shown.
